UNITED STATES PATENT OFFICE.

HERMAN R. FREUND, OF BROOKLYN, NEW YORK, ASSIGNOR TO INTERTYPE CORPORATION, OF BROOKLYN, NEW YORK, A CORPORATION OF NEW YORK.

MATRIX-DISTRIBUTING MECHANISM FOR TYPOGRAPHICAL MACHINES.

Application filed May 10, 1923. Serial No. 638,052.

The present invention relates to improvements in typographical machines and more particularly to those of the linotype class, as shown and described generally in Letters 5 Patent No. 436,532, granted to O. Mergenthaler, wherein matrices of a font stored in a magazine are released therefrom under control of a keyboard, assembled in a line which is justified, and a cast is taken there- 10 from, after which the matrices composing the line are separated and distributed according to the different characters or letters of the font, whereby the different matrices of the font are returned to the respective 15 channels of the magazine from which they were drawn.

In the commercial development of machines of this class, a demand arose for machines capable of assembling in a line matrices belonging to two or more different fonts, which required distribution of the 20 matrices not only according to the different characters or letters of the font, but also according to the different fonts to which the 25 matrices belonged, in order that the matrices would be returned to the appropriate channels of the particular magazines from which they were drawn.

The primary object of the present invention 30 is to provide novel and improved means by which a mixed line, i. e., a line containing matrices belonging to different fonts, is first separated and distributed according to the characters of the font, after which the 35 matrices thus separated are distributed to the proper magazines, according to font, whereby the distribution and the return of the matrices to the appropriate channels of the particular magazines from which they were 40 drawn may be accomplished with facility and with certainty and by a relatively simple and easily accessible structure.

To these and other ends, the invention consists in certain improvements and combinations 45 and arrangements of parts, all as will be hereinafter more fully described, the features of novelty being pointed out particularly in the claims at the end of the specification.

50 In the accompanying drawings:—

Figure 1 represents a section taken vertically through matrix-separating and distributing means constructed in accordance with the present invention;

55 Figure 2 represents, on an enlarged scale

and partly in section, the font distributor constituting a part of the matrix distributing means;

Figure 3 represents a vertical section 60 through a portion of the font distributor and the adjacent portion of one of the cooperative magazine entrances, illustrating diagrammatically the manner in which matrices appropriate to such magazine entrance are disengaged from the font distinguishing 65 means of the font distributor and caused to enter the magazine entrance;

Figure 4 is a perspective view of one of the matrices suitable for use in conjunction with the distributing means of the present 70 invention;

Figure 5 represents a vertical section 75 through the font distributor illustrating diagrammatically the relative positions of matrices belonging to different fonts, while such matrices are passing therethrough;

Figures 6, 7, 8 and 9 are side views of 80 matrices belonging respectively to different fonts and provided with distinguishing means by which they are separated and distributed according to font;

Figures 10, 11, 12 and 13 are end views 85 of the matrices shown in Figures 6, 7, 8 and 9, respectively; and

Figure 14 represents a horizontal trans- 90 verse section through a portion of the font distributor illustrating the relative positions occupied by the matrices shown in Figures 6, 7, 8 and 9, respectively, within the font distributor.

Similar parts are designated by the same 95 reference characters in the several views.

The present invention is applicable generally to typographical machines adapted for the assembling of mixed lines of matrices, it being more particularly applicable to machines of the linotype class. The preferred embodiment of the invention is shown in the accompanying drawings and will be hereinafter described in detail, but it is to 100 be understood that the invention is not restricted to the precise construction shown, as equivalent constructions are contemplated and these will be included within the scope 105 of the claims.

In machines of the linotype class and as is disclosed in the Mergenthaler patent hereinbefore referred to, the matrices which were used in the line from which a cast has been 110 taken, are separated according to the differ-

ent characters or letters of the font, preparatory to their return to the appropriate channels of the magazine from which they were drawn, by a permuted or combination bar 1 along the underside of which the matrices are caused to travel by distributor screws 2, the upper ends of the matrices having notches in which permuted or combination teeth similar to the permuted teeth m' (Figs. 4, 6, 7, 8 and 9) are formed to engage and suspend the matrices from the bar 1, the teeth of the different matrices and the bar 1 being so permuted that the matrices will drop from the bar at different points in its length, according to the channels of the magazine in which matrices belong. A magazine channel entrance similar to the entrance 3 shown in the present instance, is generally used between the distributor bar and the upper end of the magazine, to receive the matrices dropping from the distributor bar and to direct them into the appropriate channels of the magazine.

According to the present invention, the matrices used in the line from which a cast has been taken may be separated according to the characters or letters of the font or fonts, by employing a permuted or combination bar 1 and corresponding permuted or combination teeth m' in the matrices, substantially as is done in machines of the lino-type class, or equivalent means, the matrices thus separated according to character or letter being delivered to the entrance 3. However, in carrying out the present invention, a plurality of magazines 4, 5, 6 and 7 are mounted in superposed or other suitable relation in the machine, these magazines being adapted to contain different fonts of matrices, and a font distributor is arranged to receive the matrices which have been separated according to character or letter and to distinguish and distribute these matrices into the appropriate magazines according to the fonts to which they belong.

Preferably and as shown in the present instance, the font distributor 8 is interposed between the lower or discharge end of the entrance 3 and the magazines, it being preferably arranged in alignment between the lower end of the entrance 3 and the uppermost magazine. The font distributor comprises a top plate 9, a bottom plate 10 and dividing walls or partitions 11, the top and bottom plates being formed with grooves or channels 12, the channels or grooves of the top plate being directly above those of the bottom plate, and these grooves or channels are adapted to receive the lugs or ears m^2 on the corners of the matrices, the matrices being thereby retained in vertical edgewise position when they enter the font distributor from the respective channels or passages of the entrance 3. The upper or receiving ends of the grooves or channels 9 and 10 are pref-

erably flared, as shown at 13, to facilitate the entry of the matrices into the font distributor and thus avoid clogging. From the grooves or channels 9 and 10, the matrices pass into cells or passages formed between the vertical dividing walls or partitions 11, these cells or passages being aligned with the corresponding matrix-receiving grooves or channels in the uppermost magazine 4. The bottom wall of the font distributor is cut away for a considerable portion of its length, and magazine entrances 14, 15 and 16 for the magazines 5, 6 and 7, respectively are located beneath the cut away portion to receive matrices delivered from the font distributor and belonging respectively to such magazines.

According to the present invention, the font distributor is constructed to cooperate with matrices belonging to different fonts, these matrices having novel characteristics which distinguish them according to font, whereby the matrices undergoing distribution will either pass directly through the font distributor into the uppermost magazine 4, or will be released at one or another point in the length of the font distributor and will be delivered therefrom and directed into one of the magazines 5, 6 or 7. To accomplish this purpose, each dividing wall 11 or partition 11 of the font distributor has projecting laterally therefrom a rail 17 which serves as a support for the matrices while contained in or passing through the font distributor, this rail being permuted so that when a matrix reaches the point on the rail 17 where the permutations thereof correspond with the permutations of the matrix, the latter is released and is permitted to drop through the cut away portion in the lower wall of the font distributor, the matrix so released entering the appropriate magazine 5, 6 or 7 through the respective entrance 14, 15 or 16. Preferably and as shown, the portions 11^a constitute the permutation for the matrices belonging in the magazine 5, the portions 11^b the permutations for the matrices belonging in the magazine 6, and the portions 11^c the permutations for the matrices belonging in the magazine 7, these permutations being produced by suitably interrupting the rail 17, so as to form interruptions of different relative lengths and spacings.

The matrices are provided with corresponding permutations which distinguish them according to the different fonts to which they belong. For example, Figures 6, 7, 8 and 9 show matrices all having the same tooth combination m' which distinguishes them according to character, and also permutations which may be used on these matrices to distinguish them accord-

ing to font so that they may be used respectively in the magazines 4, 5, 6 and 7. The matrix M^4 (Fig. 6) is formed in its side with a recess or groove m^4 , this groove extending from end-to-end of the matrix and being continuous so that it will bridge the interruptions on the rail 17, and hence a matrix so formed will pass directly through the font distributor into the magazine 4, all 10 matrices belonging to the font contained in that magazine being formed with a similar recess or groove m^4 . The matrices M^5 , M^6 and M^7 shown in Figures 7, 8 and 9, and belonging in the magazines 5, 6 and 7, respectively, are formed with recesses or grooves m^5 , m^6 and m^7 , respectively, the upper edge 15 of the recess or groove m^5 of the matrix M^5 (Fig. 7) being notched or cut away to form permutations m^8 corresponding with the permutations 20 11^a of the rail, the matrix M^6 (Fig. 8) being provided on the upper edge of its side notch or recess with permutations m^9 corresponding with the permutations 11^b in the rail, and the matrix M^7 (Fig. 9) having permutations m^{10} in the upper side of its side notch or channel corresponding with the permutations 11^c of the rail 17. By so 25 constructing the matrices belonging to the different fonts, all matrices like the matrix M^5 (Fig. 7) belonging in the magazine 5, will be able to drop from the permuted rail 17 when such matrices reach the permutations 11^a therein; all matrices like the matrix M^6 (Fig. 8) which belong in the magazine 6 will be able to drop from the permuted rail 17 when such matrices reach the permutations 11^b therein. 30

It is preferable to provide the matrices with additional font distinguishing means 40 in order to further facilitate and insure the prompt release of the matrices when they reach the respective points at which the permutations for the respective matrices are located. To these ends, it is preferable to 45 form the side recesses or grooves m^4 , m^5 , m^6 , and m^7 in the different matrices of different widths, the notch or groove m^4 being of maximum width, while the grooves m^5 , m^6 and m^7 regularly diminish in width, the 50 diminution in the widths of the grooves being effected by locating the upper edges of the recesses or grooves closer to the center of the matrix, and arranging the lower edges of the recesses on the common level 55 O—O, Figures 10, 11, 12 and 13, from which it will be understood that the matrices belonging to different fonts will hang or be suspended at different relative elevations on the permuted rail 17, substantially as shown 60 in Figures 5 and 14. The font distributor is correspondingly formed with stepped shoulders 18, 19 and 20 in its top wall 9, these shoulders being so located with respect to the permutations 11^a , 11^b and 11^c , respectively, that the matrices like the matrix M^4 (Fig. 6) and belonging in the magazine 4 will clear all of the shoulders 18, 19 and 20 as such matrices will occupy the lowermost position on the permuted rail 17, and hence such matrices will pass the shoulders 20 and 70 19, but the foremost edge or the foot of such matrices will engage the shoulder 18. As the permutations m^8 of these matrices will then register with the corresponding permutations 11^a in the rail, these matrices will 75 promptly drop edgewise and by gravity from the rail through the cut away bottom of the font distributor and into the entrance 14 of the magazine 4. Similarly the matrices like the matrix M^6 belonging in the magazine 6 will pass the shoulder 20, but will strike the shoulder 19 in the font distributor, their permutations m^9 registering at this point with the corresponding permutations 11^b of the rail, so that these matrices 80 will be promptly released from the font distributor into the entrance 15 of the magazine 6, and all matrices like the matrix M^7 (Fig. 9) belonging in the magazine 7 will 85 strike the first shoulder 20, at which time 90 their permutations m^{10} will register with the corresponding permutations 11^c of the rail, such matrices being thus caused to drop promptly from the font distributor into the entrance 16, thence passing into the magazine 95 7.

The present invention enables matrices belonging to a plurality of fonts to be distinguished, separated and distributed to their appropriate magazines with speed, facility and certainty. The matrices, after being first distinguished and separated in the ordinary way according to the characters or letters which they bear, pass into the font distributor by which they are distinguished, and separated according to the fonts to which they belong, and are distributed to their appropriate magazines. While the matrices are in or passing through the font distributor they are suspended from and 100 they gravitate along the downwardly inclined rail 17, and when the matrices reach their corresponding permutations in this rail they are released and are delivered therefrom vertically in a true edgewise direction 105 and by gravity, the delivered matrices thus dropping directly into the respective entrances leading to their corresponding magazines. By employing the graduated or stepped stops 18, 19 and 20 and correspondingly graduating or permuting the side recesses or grooves in the matrices belonging to the different fonts, the stopping points for the matrices where the permutations thereon 110 will register with the respective permutations on the rail 17 are precisely determined, thus insuring free and prompt release and dropping of the matrices without lateral frictional contact with the dividing wall or 115 partition 11. 120

It will be understood that while the invention is herein shown and described as applied to means for separating and distributing matrices into four magazines, yet by suitably changing the longitudinal side grooves in the matrices and the permutations between their ears and also the permuted rail of the font distributor, the invention can be applied to the separation and distribution of matrices to a larger number of magazines.

The embodiment of the invention herein shown is not only simple in its construction, but the matrix passages are easily accessible, should such become necessary. For example, to render the upper ends of the magazines 5, 6 and 7 accessible, the channel entrances 14, 15 and 16, which are preferably combined or formed as one unit, as shown, are hinged at 21 so that when the structure is rearwardly or toward the left in Figure 1, the upper ends of the matrix channels in these magazines will be uncovered and also the under side of the font distributor 8, through which the matrices are delivered therefrom, will be exposed. Also, the upper end of the font distributor may be hinged, as at 22, so that it may be swung upwardly if desired to uncover the upper end of the magazine 4, the lower end of the entrance 3 or the under side of the font distributor.

I claim as my invention:—

1. In a typographical machine having means for distributing matrices according to character, means to cooperate with the first-mentioned distributing means for distributing matrices according to font comprising a rail for supporting the matrices while pendent from and travelling by gravity edgewise along the rail, the rail having permutations to correspond with permutations on the matrices and means for arresting the travel of the matrices at relatively different points along the rail, whereby the matrices are adapted to drop by gravity in the same vertical plane in which they travel along the rail when the permutations of the matrices come into register with the corresponding permutations of the rail.
2. In a typographical machine having a distributor for separating matrices according to character, means for separating matrices according to font comprising a matrix-supporting rail having permutations to correspond with permutations on the matrices and from which the matrices are suspended while travelling endwise thereon, and means for stopping the different font matrices at relatively different points along the rail whereby permutations of the rail will cause the matrices to drop directly edgewise therefrom by gravity when the matrices having corresponding permutations register with the respective permutations of the rail.
3. In a typographical machine having a

primary distributor for the separation of matrices according to character, a secondary distributor for separating matrices of like character according to font comprising an inclined permuted rail for supporting matrices to travel by gravity in an endwise direction and from which the matrices are suspended to drop directly edgewise from the rail for delivery to the appropriate magazine, and means conforming respectively with the different font matrices for stopping the latter at the corresponding permutations of the rail.

4. In a typographical machine, a distributor for separating matrices according to font comprising an inclined permuted rail along which the matrices are adapted to travel by gravity endwise and from which the matrices are suspended, the permutations of the rail corresponding with permutations in the matrices and means for arresting the travel of the matrices along the rail as they reach the corresponding permutations thereof, thereby causing the matrices to drop by gravity and in direct edgewise direction from the rail.

5. In a typographical machine, a distributor for separating matrices according to font comprising a permuted rail, and matrices each having a single groove extending longitudinally throughout its length to receive and to suspend the matrices from said rail, the upper edges of the grooves of the matrices suspended on the rail being located differently on the matrices of different fonts and permuted to correspond with the permutations of the rail and means located in conformity with the upper edges of the grooves of the different font matrices to arrest the movements of the matrices along the rail when the permutations of the matrices reach the respective permutations of the rail.

6. In a typographical machine, a distributor for separating matrices according to font comprising a rail having permutations therein distinguished according to fonts, and matrices belonging to different fonts and each having a single groove in its side extending longitudinally thereof to receive the rail and to suspend the matrix therefrom, the matrices of different fonts being thereby supported in relatively different positions on the rail and the uppermost sides of the grooves in the matrices suspended on the rail having permutations distinguished according to fonts for causing edgewise dropping of the matrices from the rail when the matrices reach the corresponding permutations of the rail, and means for setting the matrices of the different fonts relatively to the corresponding permutations of the rail.

7. In a typographical machine, a distributor for separating matrices according to font comprising a permuted rail along which correspondingly permuted matrices belong.

ing to different fonts are adapted to travel endwise in different relative positions and from which such matrices are adapted to be released by gravity, and stops distinguished 5 in their positions relatively to said rail according to the relative positions occupied by the different font matrices on the rail and located to cooperate with the corresponding permutations of the rail to cause delivery of 10 the matrices therefrom.

8. In a typographical machine, a distributor for separating matrices according to font comprising a rail having permutations distinguished according to fonts and along 15 which matrices having corresponding permutations are adapted to travel while suspended in different relative positions therefrom, and stops distinguished in their positions relatively to the rail according to the 20 relative positions of the different font matrices on the rail and located to cooperate with the corresponding permutations of the rail to cause dropping of the matrices therefrom by gravity.

25 9. In a typographical machine, a distributor for separating matrices according to font comprising a matrix guiding channel, a permuted rail along which matrices having a groove located at a predetermined distance from its edge to determine its height 30 on such rail and permutations corresponding with those of the rail are adapted to travel, and a stop located at a predetermined point in the channel to be engaged by and to check 35 such matrices therein for delivery therefrom in accordance with said permutations.

10. In a typographical machine, a distributor for separating matrices according to fonts comprising a channel along which 40 matrices are guided to travel, a permuted rail arranged to support thereon at different heights matrices travelling in said channel, the matrices being permuted according to

fonts and in correspondence with the permutations of the rail, and stops located at different heights in said channel according to 45 fonts and operative respectively to check the matrices travelling at the different heights in positions to conform with their corresponding permutations of the rail to effect 50 release of the matrices therefrom.

11. In a typographical machine, a distributor for separating matrices according to fonts comprising a permuted rail for supporting correspondingly permuted matrices 55 to travel in different relative positions thereon according to the different fonts to which they belong, and stops distinguished in their positions relatively to said rail according to the 60 positions occupied by the different font matrices while travelling along the rail and operative to check the travel of the matrices when they reach positions along the rail where the permutations of the matrices conform with those of the rail.

12. In a typographical machine having a primary distributor for separating matrices according to character, a secondary distributor arranged to receive separated matrices of like character and to separate them according to font, comprising channels each to receive and guide matrices of like character, a permuted rail from which the matrices of different fonts are supported at different 70 relative heights and along which they 75 travel, and stops in said channel distinguished in their positions relatively to the rail according to the heights of the different font matrices on the rail and operative to check the matrices in the channel according to font for effecting the release and discharge thereof.

In testimony whereof I have hereunto set my hand.

HERMAN R. FREUND.
